STRAIN RELIEF DEVICE

Hugh H. Eby, Jenkintown, Pa., assignor to Penn Electric Development Corporation, Philadelphia, Pa., a corporation of Pennsylvania

Application September 15, 1938, Serial No. 230,091

3 Claims. (Cl. 173—322)

This invention relates to strain relief devices, and particularly to devices for application to electric conductors to absorb tensioning strains impressed upon the conductors, relative to housings, mountings or terminals for the conductors.

In the low voltage electrical field, it is common to provide cords and disconnecting plugs attached thereto and arranged for more or less frequent connection and disconnection from the sockets of electrical appliances. In the past, the tensile strain required for the disconnection frequently has been placed upon the current carrying wire in the cord, usually having a focal point for the stress at the connection of such wire with the screw or other anchor to the metal element of the terminal. Repeated attachment and detachment by withdrawing tension on the cord ultimately stresses the wire to the point of rupture at or adjacent to the screw, resulting in open circuits, short circuits, and in fire hazards, especially in the case of domestic appliances. Obviously similar disadvantages maintain in the case of permanent wire connections to the base of a lamp, fan, or the like, in that through accidents, falling and tripping over, or dropping articles upon the wire connections similar separating strains are imparted to the points of attachment of the wire or cord.

It is among the objects of the invention: to provide an improved strain relief device; to provide a strain relief device which retains a firm grip frictionally without additional fastening or securing means; to improve the art of strain reliefs; to provide a mounting device for operative association with a strain relief and a mounting support in a novel and efficient manner; to provide a strain relief which relies upon distortion of the cord for part of its frictional effect; to provide a strain relief which is effective against both torsion and tension; to provide a strain relief of extreme economy of manufacture and applications; to provide a strain relief comprising an open jawed member having a plurality of inclined teeth such as to resist retraction from the wire in a direction opposite to the direction of attachment; to provide a strain relief comprising an open jawed inwardly toothed element arranged to frictionally grasp a wire and to resist movement on the wire in any direction; to provide a strain relief comprising a pair of oppositely disposed open jawed inwardly and rearwardly toothed devices arranged to frictionally engage a wire and to frictionally remain in engagement therewith without additional securing devices, to resist a maximum pull; and

many other objects and advantages as will become more apparent as the description proceeds.

In the accompanying drawing forming part of this description:

5 Fig. 1 represents a plan of a preferred form of strain relief element of value of and by itself, and of particular value when used with a duplicate or complementary element, turned at 180° thereto.

10 Fig. 2 represents a plan of a modified form of relief element, also usable singly or in duplicate.

Fig. 3 represents a side elevation partially in section, of an appliance base, with a metallic attaching pan anchored to both the base and a 15 fragmentary portion of a connector or wire cord, to anchor the cord by its housed strain relief to the wall of the base.

20 Fig. 4 represents a transverse section through a wire connector with the form of strain relief element shown in Fig. 2 in duplicate in the pan device of Fig. 3.

Fig. 5 represents a fragmentary side elevation of the same.

25 Fig. 6 represents a fragmentary perspective of the same.

Fig. 7 represents a transverse diametric section through the same.

30 Fig. 8 represents an enlarged fragmentary side elevation of a portion of connector or cord with a pair of the relief elements of Fig. 1, or the like disposed in anchored contiguous relation thereto, as accomplished manually, or by any suitable machine.

Fig. 9 represents a transverse section through 35 the cord shown in Fig. 8, with the pair of relief devices of Fig. 1 in anchored engagement thereon.

It is to be understood that the strain relief elements may be made of various materials, including various kinds of metals, for certain installations, but that in the main it is preferred that some insulating and relatively cheap material such as vulcanized fiber, or a phenolic condensation product, will be used. Usually and preferably it is such as conduces to production by 40 stamping operations.

Referring to Fig. 1, the element 10 is preferably and generally U-shape in plan, having the central connecting web portion 11, the inner surface 12 of which is preferably generally ar- 45 cuate or curved to receive, although not neces- sarily to fit, the curved surface of the wire to be engaged. From the median or central portion 11, a leg 13 extends, having the internal rear- 50 wardly extending pointed serrations or teeth 14, and having the outwardly flared guiding mouth

portion 15 terminating in a rearward shoulder or supplemental tooth 9. Tooth 9 may be undercut, or be substantially square as shown. On the outer surface, the element may be substantially round or any other shape such as oval, or angular and it may have the ear 16 or the like to assist in prevention of rotation of the element in a suitable support as will be later described. Generally parallel to leg 13, in spaced relation thereto, the leg 17 is disposed having the rearwardly or inwardly projecting teeth 18 or serrations, having the outwardly flared mouth surface 20 complementary to opposite surface 15, so as to guide a wire between them. Its outer surface, substantially diametrically opposite to ear 16, has the ear 21. Guide surface 20 terminates in the undercut or square tooth 19. It will be observed that the two spaced legs respectively 13 and 17 have such relation as to effect a wire cord receiving slot 22 having the flared guiding mouth defined by the outward surfaces 15 and 20 respectively. It is to be observed that the slot preferably has appreciable length, at least greater than the radius of the disc and has inward rearward teeth on both sides.

In Fig. 2, the substantially annular element 23 may have the arcuate outer surface shown, or may have the ears 16 and 21 of Fig. 1, or the like disposed diametrically on the element or, as may be true of all forms, it may have a polygonal outline if desired.

Inwardly the element 23 has a slot 24 formed by the legs 25 and 26, and the surface of which is formed of the outer flared surfaces 27 and 28, respectively, and the inwardly directed rearwardly extending serrations or teeth 30 and 31, respectively. On the connecting web portion 29, in line with the slot 24, is the spike or pointed tongue 32, arranged to divide or separate portions of an impaled cord, to force the portions laterally into locked engagement with teeth 30 and 31 as will be clear, or will become so as the description proceeds.

Externally element 23 is shown as having a plurality of diametrically oppositely disposed angular notches, as at 61. The notches 61 are for the purpose of facilitating anchoring engagement of strain element 23 with its ultimate support on another element or the prevention of relative rotation of the relief element and its ultimate support.

It will be apparent that with the assembly of Fig. 4, it will be possible to dispose another duplicate element such as is shown in that figure or in Fig. 1 with suitable external contouring in parallel contiguous but reversed relation on the connection, so that the slot 24 of the first element is mounted on the wire adjacent or contiguous to the above element, and so that when both are forced upon the wire, the lateral notches 61 of one element will register with the respective notches 61 of the second mentioned reversed element.

It will be apparent that either of the elements shown in the figures may be used as above to good effect. Thus element 10 of Fig. 1 and element 23 of Fig. 2 may each be forced laterally upon a connector until an edge thereof, engages the inner surface of the element, at 12 in Fig. 1, or impaled on the spike 32, of Fig. 2, respectively, to lateral impalement upon the rearwardly projecting teeth 9, 14, 19 and 18, of Fig. 1, or 30 and 31 of Fig. 2 with such biting engagement in the insulators of the connector that it requires a veritable tearing of the insulation to secure

relative axial movement of the wire or connector and the strain relief element. It will be understood that the anchoring engagement between the strain relief and connector is considerably enhanced by providing the elements in complementary relatively reversed pairs, as shown in Figs. 4, 8 and 9, the strain relief elements 10 of Fig. 1 are provided in reversed duplicate and each reinforces the other and enhances its relative anchoring effect. It is to be noted that the rearward teeth have insulation and the like squeezed upon them to insure anchoring. It is an interesting fact that instead of the close adjacency shown in Fig. 8, it is sometimes a means to an even better anchorage if the planar members are slightly separated so that insulation may be distorted from the surface between the elements, as it piles up on the teeth of the complementary element. It has been found possible at least to double the tensile strength of a single element by arranging them in pairs, either in contacting adjacency or in slightly spaced relation.

It is preferred in the interest of both economy and gripping power, that the discs or planar strain relief elements be relatively thin. This makes the rearward teeth sharp to facilitate entry with the insulators of the connectors. Of course the material should be thick enough to furnish sufficient strength for the tensile requirements.

As shown in Fig. 3 the base 55 of a fixture such as a fan, telephone, lamp, etc. has a wall 56, having an aperture 57, such as to receive axially, the sheet metal pan 58. The pan is arranged for a tight sliding fit in the aperture and is preferably open-bottomed having an axial aperture 59 of appreciable diameter, including a flange of narrow extent 60 formed on one end, and having the plurality of flange fingers in two radially staggered series, relatively long fingers 61, in staggered relation to the relatively short fingers 62. Preferably the long fingers 61 arise out of radially indented or recessed portions 64 forming internal ribs 63 arranged to rest in registering locking recesses 57 on the complementary strain relief elements 23.

When applying the assembly of a pair of strain relief elements 23 to a wire conductor 20, the cage or pan 58 is threaded over the wire, then the two strain relief elements are forced laterally on the wire until their respective lateral recesses 61 are caused to register (at which time the elements have been forced to frictionally grip the wire or connector), then the pan 58 is slid axially on the wire and over the assembled relief elements with the recessed portions or internal axial ribs 63 engaged in registering recesses and the pan engaging and covering the lateral edges of both elements after which the short legs 62 are turned over against the adjacent element 23, to hold the two elements 23 between fingers 62 and flange 60, with the wire 20 running through aperture 59 of the pan. The housed strain relief is then mounted frictionally in the opening 57 of the mounting support and fingers 61 are bent outwardly to anchor the pan and relief in the base 55.

It is to be understood that either of the toothed forms of strain reliefs may be used in the pan assembly just described and such use is contemplated.

It is to be understood that the ears 16 and 21 of the element 10 of Fig. 1, are such as to be capable of being grasped or gripped by securing or anchoring devices attached to the ears alone, if desired, or as eccentric elements on the con-

necter such as to abut suitable stops to prevent rotation of the connector and strain relief elements in an assembled terminal device.

I claim as my invention:

1. A strain relief comprising a flat disc-like element having an insulated conductor receiving slot extending from an entrance in the outer edge thereof and terminating in a closed end, the slot having an inner enlargement wider than the slot entrance, the opposing walls of which slot comprise in part at least acutely angled inclined teeth pointing toward the closed end with the pointed ends of the teeth in substantial alignment with the respective walls of the entrance of the slot, whereby the insulation of an insulated conductor pushed laterally into the slot against the closed end thereof in contact with the teeth is substantially pierced by the teeth and is disposed between the teeth, and between the teeth and the closed end of the slot to hold the conductor against torsional, lateral withdrawal and axial slipping movements.

2. A strain relief comprising an element having a pair of spaced legs and means connecting the legs together at one end forming an insulated conductor receiving slot, said slot having an internal enlargement, inwardly directed acutely angled teeth formed on the legs and extending into the slot with the teeth pointing toward the closed end of the slot with the points of the teeth closer together than the enlargement surfaces and in substantial alignment with the respective surfaces of the slot at its entrance, a supplemental impaling tooth mounted on the connecting means

and substantially bisecting the slot, the impaling tooth and adjacent teeth on the respective legs being so disposed that when an insulated conductor is forced into the slot to impalement on the impaling tooth, the insulation of a conductor is laterally distorted in the enlargement to engage and be anchored by the said adjacent teeth and held against torsional, lateral withdrawal or axial slipping movements relative to the element.

5 3. In strain reliefs an anchoring housing for mounting a strain relief operatively to the aperture in a supporting plate comprising a flat apertured wall against which a strain relief can abut laterally, the wall merging into a drawn continuous peripherally closed short cylindrical wall for engaging the peripheral edge of the strain relief to be associated therewith, said cylindrical wall having integral bendable fingers arising out of a free edge thereof arranged in an annular 10 series and arranged to be bent radially inwardly to enclose such strain relief by engaging another lateral surface thereof from that engaged by the flat wall, said cylindrical wall having a plurality of axially extending indentations forming external recesses and internal ribs, the free edge of the cylindrical wall being continued in a plurality of fingers aligned with the respective indentations and forming an annular series of smaller diameter than that formed by the first 15 mentioned fingers and arranged for radial outward bending across and beyond the first mentioned annular series of fingers.
